UNITED STATES PATENT OFFICE.

CHARLES A. BAILEY, OF CROMWELL, CONNECTICUT.

TOY PISTOL.

1,285,581.

Specification of Letters Patent. Patented Nov. 26, 1918.

Application filed June 6, 1918. Serial No. 238,568.

To all whom it may concern:

Be it known that I, CHARLES A. BAILEY, a citizen of the United States, residing at Cromwell, in the county of Middlesex and 5 State of Connecticut, have invented a new and Improved Toy Pistol, of which the following is a specification.

My invention relates more especially to that class of toy pistols used for exploding 10 what are commonly known as "paper caps," and an object of the invention, among others, is to provide a device of this class that shall be particularly efficient in operation and that may be constructed at a minimum expense.

15 One form of pistol embodying my invention and in the construction and use of which the objects herein set out, as well as others, may be attained, is illustrated in the accompanying drawings, in which—

20 Figure 1 is a view in side elevation of a pistol embodying my invention.

Fig. 2 is a view in side elevation showing the opposite side of the pistol from that shown in Fig. 1.

25 Fig. 3 is a view in cross section on plane denoted by dotted line 3—3 of Fig. 1.

Fig. 4 is a detail view showing a modified form of means for operating the cap wheel.

In that form of my invention illustrated 30 and described herein the pistol comprises a frame, constructed of metal, preferably cast to shape, and embodying a handle portion 5 and a barrel portion 6. An opening 7 is formed through the frame and a cap wheel 35 actuating spring 8 extends, as to its longer arm, across said opening and through a hole in a cap wheel 9. The spring 8 may be of any suitable form, as shown herein it being a U-shaped spring extending partially 40 around a post 10 and having its shorter arm secured in any suitable manner to a lug 11. The cap wheel is free to rotate upon the longer arm of the spring. A trigger 12 is pivotally mounted in the frame as upon a 45 pivot 13 secured in place in any suitable manner, said trigger being movable laterally on its pivot. This trigger is rigidly connected with a cap wheel rotating arm 15 and a cap wheel spring tensioning arm 50 16, the latter having preferably a forked end 17 to engage the longer arm of the spring 8.

The paper caps are placed in pockets 18 in the cap wheel and in operation, the trigger being pulled backwardly the arm 15

engaging one of said pockets, exerts its influence to rotate the wheel on the longer arm of the spring 8 and the tensioning arm 16 operates to compress the spring and move the cap wheel away from an anvil 19 formed 60 by the upper edge of the opening 7 through the frame. At a certain period in the backward movement of the trigger the arm 17 will pass off the end of the longer arm of the spring and at the same time the arm 15 65 will pass out of the pocket in the cap wheel in which it is engaged. At the same time the cap wheel will be in position with one of the pockets directly underneath an anvil 19 and upon the arms 15 and 16 being released from the cap wheel and its spring, the wheel will be thrown forcibly upward by the longer arm of the spring 8 and bring the cap in the pocket into contact with the anvil, thus exploding the cap. After a cap 70 has been thus exploded the forefinger of the operator may be employed to rock the trigger forwardly and laterally, carrying the arms 15 and 16 upwardly into the position shown in Fig. 1 of the drawings when the operation 75 may be repeated.

In the form of the device shown in Fig. 4 a carrier is mounted in the frame and includes a trigger 20, a fulcrum point 21, a wheel carrying projection 22 and a cocking 85 end 23. The wheel is secured as by bending over the ends 24 of the projection 22. A spring 25 is rigidly secured in the frame in any suitable manner and is engaged with a notch in the carrier. The pressure of the 90 spring is toward the bearing of the fulcrum point 21 whereby it will be seen that when the carrier is moved by pressure upon the trigger 20 in one direction (as toward the right) after the spring passes a certain point 95 with respect to the fulcrum, the projection 22 and the cap wheel will be forced toward and against an anvil 26 with sufficient force to explode a paper cap. This method of operating the hammer in a toy pistol is old 100 and will be readily understood by those skilled in the art and for this reason a more detailed description and illustration are omitted herein.

In accordance with the provisions of the 105 patent statutes, I have described the principles of operation of my invention, together with the apparatus which I now consider to represent the best embodiment thereof; but I desire to have it understood that the device 110

shown is only illustrative, and that the invention may be carried out by other means.

I claim—

1. A pistol embodying a frame having an anvil, a rotatable cap wheel having means to receive a cap, means for forcing the cap wheel bodily against said anvil, and means for forcing it away from said anvil.
2. A pistol embodying a frame having an anvil, a rotatable cap wheel having means to receive a cap, mechanical means for bodily forcing the wheel against said anvil, and manually operated means for forcing it away from said anvil.
3. A pistol embodying a frame having an anvil, a rotatable cap wheel having means to receive a cap, a spring upon which said cap wheel is supported, and means for forcing the cap wheel bodily away from said anvil and to tension said spring.
4. A pistol embodying a frame having an

anvil, a rotatable cap wheel having means to receive a cap, means for forcing the wheel bodily against said anvil, and a pivotally mounted trigger having an arm operatively connected with the cap wheel to force it away from said anvil. 25

5. A pistol embodying a frame having an anvil, a cap wheel having means to receive a cap, a spring upon which said cap wheel is rotatably mounted, means for forcing the cap wheel away from said anvil, and means for rotating the cap wheel on said spring. 30

6. A pistol embodying a frame having an anvil, a cap wheel having means to receive a cap, a spring upon which said cap wheel is rotatably mounted, an arm to engage said wheel to rotate it, an arm to engage said spring to tension it, and means for operating said arms. 35

CHARLES A. BAILEY.
